ATTORNEYS.

UNITED STATES PATENT OFFICE.

ALLAN J. KEANEY, OF MOUNT VERNON, NEW YORK.

FOLDING PENCIL COMPASS.

Application filed July 8, 1925. Serial No. 42,177.

This invention relates, generally, to an improved folding pencil compass; and the invention has for its principal object to provide a folding pencil compass constructed and arranged in a novel manner so that one leg thereof, when not in use, may be folded up and into the other leg, whereby the device will possess the appearance of and may be used as an ordinary pencil.

10 Another object of this invention is to provide that leg of the compass which serves as the pencil element with an adjustable lead carrying or holding means, so that the lead may serve as the marking point of 15 the compass, and so that said lead may be advanced or retracted to bring the marking point in even adjusted relation to the pivot point provided by the foldable leg of the compass.

20 Other objects of this invention, not at this time more particularly enumerated, will be clearly understood from the following detailed description of the same.

With the various objects of this invention 25 in view, the same consists, primarily, in the novel folding pencil compass hereinafter set forth; and, the invention consists, furthermore, in the novel arrangements and combinations of the various devices and parts, 30 as well as in the details of the construction of the same, all of which will be hereinafter more fully described, and then finally embodied in the appended claims.

The invention is clearly illustrated in the 35 accompanying drawings, in which:—

Fig. 1 is a face view of the novel folding pencil compass in its folded condition; Fig. 2 is a side elevation of the same in its folded condition; Fig. 3 is a longitudinal section 40 of the folding pencil compass, the same showing the first step in unfolding the foldable leg thereof; Fig. 4 is a side elevation of the same with the foldable leg completely unfolded and extended ready for use; and Fig. 5 is a transverse section, taken on line 45 5—5 in Fig. 2, said view being drawn on an enlarged scale.

Similar characters of reference are employed in all of the hereinabove described 50 views, to indicate corresponding parts.

Referring now to said drawings, the reference character 6 indicates the pencil leg of the compass, the same consisting of a substantially cylindrical body portion, having

an extension 7 of reduced diameter at its 55 outer or free end, and a bifurcated opposite end 8 providing a central bearing or joint slot 9. Said body portion of the pencil leg 6 is provided with a longitudinally extending depressed seat, socket or compartment 60 10, which opens along the longitudinal face of the pencil leg. Rotatably engaged upon the reduced extension 7 of the pencil leg 6 is a hollow lead-holding shell 11, provided with a tapered free-end portion 12 65 through which a pencil lead 13 may be projected. Affixed within the interior of said shell 11, so as to be axially alined therein, is a tubular internally screw threaded barrel 14, through the bore of which said pencil lead 13 may be advanced. The reference character 15 indicates a lead advancing 70 plunger, the forward end of which is entered in the rearward end of said barrel 14 behind the pencil lead 13. Said plunger 15 is provided with male screw thread elements 75 16, which engage the internal screw threads of said barrel 14. Formed in the pencil leg body 6, in longitudinal alinement with said barrel 14 is an elongated socket 6', into which the rearward end-portion or tail 15' of the plunger 15 extends. The rearward extremity of said end-portion or tail 15' is provided with a flattened key-piece 15'', which serves to prevent rotation of said 80 plunger 15 relative to the pencil leg body 6, while permitting free longitudinal movement thereof; so that upon turning the pencil leg body relative to the shell 11, said plunger 15 will turn with the former and 85 its male thread elements 16 caused to cooperate with the internal threads of said barrel 14, thus producing longitudinal advancement or retraction of the plunger relative to the barrel to advance the lead 13 or 90 permit the retraction of the same, as the case may be. The described arrangement permits of easy adjustment of the pencil lead 13, as to its extent of projection from the free end of the shell 11. The above 95 described pencil lead adjusting means is not, per se, claimed by me, but is illustrative of one of many types of pencil lead controlling or adjusting means common to magazine or mechanical pencils. So far as my present 100 invention is concerned I merely desire to claim, broadly, a pencil lead controlling or adjusting means in combination with the

novel folding pencil compass structure which is the subject of my invention.

The foldable leg of my compass, comprises an articulated leg element consisting of a main leg section 17 and a foldable free end or pointed section 18. Said main leg section 17 is provided at its upper end with a perforate hinge leaf 19, adapted to be received in the bearing or joint slot 9 of the bifurcated end 8 of the pencil leg body 6, and thereupon pivotally connected with the latter by means of suitable connection. Since it is desirable in a compass instrument, that the respective legs thereof be so pivotally joined as to readily maintain the positions to which they are adjusted, I have provided a frictional pivot joint adapted to conveniently serve such end. This frictional pivot joint is formed by providing external seats 20 at the opposite outer faces of said bifurcated end 8 of the pencil leg body 6, the same being in parallel plane with said bearing or joint slot 9. A pivot yoke member 21 having laterally spaced washer or yoke-arms 22 and 23 is caused to embrace the bifurcated end 8 of the pencil leg body 6, so that said washer or yoke-arms 22 and 23 respectively seat themselves in the respective seats 20. One of said washer or yoke-arms, 30 as 23, is provided with an internally threaded perforation, so that a pivot screw 24, when passed through the opposite washer or yoke-arm 22, and thence through the interengaged bifurcated end 8 and hinge leaf 19 35 of the respective compass leg portions, may be threaded into said washer or yoke-arm 23, with the effect of drawing the interengaged parts together in frictional embrace, whereby the compass leg portions may be 40 swung relatively one to the other, when sufficient force is applied thereto to overcome the thus established friction, but will, in consequence of such established friction, tend to hold or maintain the positions to 45 which they are thereby adjusted. The pivot yoke member 21 may be provided, at its outer end with a socket 25 adapted to hold an eraser rubber 26 as shown. It will be quite evident that the socketed eraser holding portion may be omitted from the structure if desired, and the washer or yoke-arms 22 and 23 may be made and used in the form of independent washers.

The outlying body portion of the main leg section 17 is provided with a longitudinal slot or socket 27. Pivotally connected by the rivet 28, within the outer end of said socket or slot 27, is the butt 29 of said foldable free end or pointed section 18. By turning said section 18 on its pivotal connection, the same may be swung or folded into the slot or socket 27 of the section 17, as illustrated in Figs. 1 to 3 inclusive of the drawings. Secured by its anchor piece 30, which 55 is inserted within the rear end of said slot

or socket 27 and riveted to the section 17, is a clasp-spring 31, which extends longitudinally along one side of said slot or socket 27 above the folded in section 18. The free end of said clasp-spring 31 bears tensionally down upon the butt 29 of the section 18, thus holding the latter yieldably retained in its in-folded position. Said butt 29 of the section 18 possesses a rounded kick portion 32, which, when the section 18 is out turned from the section 17 lifts the free end of the clasp-spring 31. Said kick portion 32 terminates in the outer side of the butt 29 in a flat seat 33, at the inner end of which is a stop-shoulder 34. When the section 18 is out turned from the section 17, into unfolded or operative extended position relative to the latter, the clasp-spring 31 will bear tensionally upon said flat seat 33 to yieldably hold the parts in such relation, while the stop-shoulder 34 will fetch up against the end of the clasp-spring, thus holding the unfolded section 18 against outward yielding and collapse; all of which will be understood from an inspection of Fig. 4 of the drawings.

As will be evident from a reading of the accompanying drawings, the foldable leg of the pencil compass may be snugly folded into the pencil leg thereof by, first, folding the foldable section 18 into the section 17, and thereupon, in turn, swinging the section 17 into the socket or compartment 10 of the pencil leg 6, so that the foldable compass leg is flushly concealed within the latter. It will be quite obvious that a very neat and compact arrangement results, whereby the device will have the appearance of and may be used as an ordinary pencil. In order to facilitate the unfolding operations, the side of the section 17 of the foldable leg is provided with a thumb-nail nick 35, and the pencil leg body 6 is provided with a cut-away portion or clearance notch 36, with which said nick 35 registers when the parts are folded together, so that the nick may be engaged by the thumb-nail of the user to lift the section 17 to desired outwardly moved or unfolded position. In like manner, the foldable section 18 is also provided in one side of its body with a thumb-nail nick 37, which, when the section 18 is folded into the section 17, registers with a cutaway portion or clearance notch 38 provided in the latter to give access to said nick.

I am aware that some changes may be made in the general arrangements and combinations of the various devices and parts, as well as in the details of the construction of the same, without departing from the scope of this invention as described in the foregoing specification, and as defined in the appended claims. Hence, I do not limit my invention to the exact arrangements and combinations of the devices and parts as

set forth in the foregoing specification, nor do I confine myself to the exact details of the construction of said parts as illustrated in the accompanying drawings.

5 I claim:—

1. A folding pencil compass consisting of a pencil leg having a lead holding and adjusting means at its free end, said pencil leg having an elongated socket in one side

10 thereof; a foldable leg comprising a main section, a foldable pointed section pivoted to the outer end of said main section, said main section having a longitudinal slot into which said foldable section may be folded,

15 means for retaining said foldable section either in folded or extended relation to said main section; and means for pivotally interconnecting said pencil leg and said foldable leg so that the latter, when its members are

20 folded together, may be in turn folded into and flushly concealed in said side socket of said pencil leg.

2. A folding pencil compass consisting of a pencil leg having a lead holding and adjusting means at its free end, said pencil leg having an elongated socket in one side there-

25 of; a foldable leg comprising a main section, a foldable pointed section pivoted to the outer end of said main section, said main section having a longitudinal slot into which said foldable section may be folded,

30 means for retaining said foldable section either in folded or extended relation to said main section; means providing a friction

35 joint for movably interconnecting said pencil leg and foldable leg together; and said foldable leg, when its members are foldable together, being movable into said side socket of said pencil leg to flushly con-

40 seal the same therein.

3. A folding pencil compass consisting of a pencil leg having a lead holding and adjusting means at its free end, said pencil leg having an elongated socket in one side there-

45 of; a foldable leg comprising a main section having a longitudinal slot in its free end, a pointed foldable extension pivoted to the free end of said main section so as to

fold into the slot of the latter, a clasp-spring secured to said main section, means 50 in connection with the pivoted end of said foldable extension engageable by the free end of said clasp spring to hold said extension in either folded or extended relation to said main section; and means for pivotally 55 interconnecting said pencil leg and said foldable leg so that the latter, when its extension is in folded relation thereto, may be in turn folded into and flushly concealed in said side socket of said pencil leg. 60

4. A folding pencil compass consisting of a pencil leg having a lead holding and adjusting means at its free end, said pencil leg having an elongated socket in one side there- 65 of; a foldable leg comprising a main sec-
tion having a longitudinal slot in its free end, a pointed foldable extension pivoted to the free end of said main section so as to fold into the slot of the latter, a clasp-spring secured to said main section, means 70 in connection with the pivoted end of said foldable extension engageable by the free end of said clasp spring to hold said extension in either folded or extended relation to said main section; means providing a fric- 75 tion joint for movably interconnecting said pencil leg and foldable leg together; and said foldable leg, when its extension is in folded relation thereto, being movable into said side socket of said pencil leg to flushly 80 conceal the same therein.

5. A folding pencil compass, comprising a pencil body having a longitudinal socket in its side, a foldable leg pivotally connected with said pencil body to fold into said 85 socket, said foldable leg having a pointed extension pivotally connected with its free end, said foldable leg also having a socket into which said pointed extension may be folded, and means for holding said exten- 90 sion in either folded or extended relation to said foldable leg.

In testimony that I claim the invention set forth above I have hereunto set my hand this 3rd day of July, 1925.

ALLAN J. KEANEY.
